UNITED STATES PATENT OFFICE.

STUART A. COGSDILL, OF DETROIT, MICHIGAN, ASSIGNOR TO DETROIT REAMER
SALVAGE CO., OF DETROIT, MICHIGAN, A CORPORATION OF MICHIGAN.

METHOD OF SALVAGING REAMERS OR LIKE TOOLS.

1,267,514.

Specification of Letters Patent.

Patented May 28, 1918.

Application filed May 21, 1917. Serial No. 169,898.

To all whom it may concern:

Be it known that I, STUART A. COGSDILL, a citizen of the United States of America, residing at Detroit, in the county of Wayne 5 and State of Michigan, have invented certain new and useful Improvements in Methods of Salvaging Reamers or like Tools, of which the following is a specification, reference being had therein to the accompanying drawings.

This invention relates to a method of salvaging reamers which have become worn down or broken in use and refers more particularly to the method of restoring and re-centering reamers or like tools, such as drills or the like.

When tools of this type become worn or particularly when they become broken, it is customary to discard them.

20 The present invention contemplates a method whereby the worn or broken reamers may be salvaged and made just as suitable for use as new reamers. The invention also contemplates a method in which the reamer 25 can be re-centered and re-ground without the employment of extraneous devices; to provide a method in which the reamer is accurately ground by using the new center as the axis about which it is moved in re-30 trimming or re-grinding; to provide a method whereby worn or broken reamers can be restored to operative condition at slight expense; and in general to provide a new and improved method for salvaging 35 reamers or the like.

In the drawings:

Figure 1 represents a broken reamer to be salvaged;

Fig. 2 represents a method of grinding 40 the male center on the end of the reamer;

Fig. 3 illustrates the manner in which the flutes are salvaged;

Fig. 4 illustrates the reamer of Fig. 3 completed;

45 Fig. 5 is a fragmentary view showing the modified method of grinding the male center of the reamer.

Describing in detail the improved method and referring to the drawings in which the 50 manner of carrying out this method is illustrated; A designates a reamer which, as shown in Fig. 1, has been broken, as indicated at B, in use. If the reamer is so broken it is necessary to grind the end of the 55 reamer to the line designated by C in order

for a proper cutting end to be formed on the reamer. In grinding this end to the line C, I perform the operation in such a manner as to provide a male center D. This may be accomplished in various ways; thus in Fig. 60 2 it is shown by employing a grinding periphery E for cutting down the main portion of the reamer by moving it inward to the line E', indicated in dotted lines, and then forming the male center D by moving 65 a grinding wheel F having a beveled periphery F' inwardly to the position shown in dotted lines.

A still further method, and one which in many cases is preferable because of its 70 simplicity, consists in arranging a cylindrical shaped grinding member G with its axis inclined to that of the reamer, as indicated in full lines in Fig. 5, and then causing it to travel inward to the position shown in 75 dotted lines. This arrangement has the advantage of both grinding off the main body portion and simultaneously forming the male center D.

When the reamer is broken, as indicated 80 in Fig. 1, the fluted portion is necessarily materially shortened as the forward end of the reamer is ground down. In some instances this shortening of the fluted portion of the reamer would make the latter unfit 85 for use. I, therefore, grind the flutes H back a sufficient distance, as indicated in Fig. 3, to provide the necessary length for this portion of the reamer. This operation, of course, is not necessary where the forward 90 end of the reamer does not have to be ground down to a material extent.

In the usual construction of reamers the forward portion of the flutes, which is designated by H, are of greater diameter than 95 the intermediate or plain surface of the reamer, designated by J. It therefore becomes necessary to restore these surfaces after the fluted portion is lengthened by grinding to the same relative proportions 100 employed in the original tool. To accomplish this result after the center is formed on the reamer, I grind down the plain surface, designated by J, until it is of lesser diameter than the fluted section H. The fluted portion is then ground down to provide proper proportioning and in this operation the fluted portions are provided with suitable cutting edges as will be readily understood. In both cases the device in being re-ground is 110

centered about the new male center and the original center K on the tang end of the reamer and thus the cutting edges will be automatically positioned with reference to 5 the male center.

While the diameter of the reamers will be somewhat lessened where it is necessary to re-grind the fluted portion, the only difference in the salvaged reamer will be in the 10 size, the reamer being, however, in all respects equal to the original reamer before broken. While I have described the invention in connection with reamers, in its broader aspects it is not limited to the particular tool mentioned as it is also applicable to salvaging drills or other tools of this same 15 general character.

What I claim as my invention is:—

1. The method of salvaging reamers or

like tools which comprises cutting down the 20 tool to form a male projection on the cutting end thereof and using the projection thus formed as a centering device while re-grinding the tool.

2. The method of salvaging reamers having 25 a plain body portion and fluted portion of greater diameter than the body portion which comprises arranging a grinding periphery so that it will cut down the end of the reamer beyond the worn or broken portion and leave a male centering device, cutting back the fluted portion to secure the necessary length of the cutting edges and re-grinding the cutting surfaces of the 30 reamer so that its axis corresponds to the 35 new male center.

In testimony whereof I affix my signature.

STUART A. COGSDILL.
